TOOTHBRUSH

Auguste L. Saltzman, Orange, N. J., assignor to
 Bristol-Myers Company, New York, N. Y., a corporation of Delaware

Application May 31, 1940, Serial No. 338,011

3 Claims. (Cl. 15—167)

The invention relates to toothbrushes; and particularly to improvements in the handles for such brushes.

An object of the invention is to provide a handle having gripping portions which are so disposed with relation to the head of the brush as to facilitate manipulation of the brush by either hand in massaging the gums, and in brushing downwardly over the upper teeth and upwardly over the lower teeth.

Another object is to provide a toothbrush in which gripping surfaces on the handle are so disposed with reference to the disposition of the head of the brush and the working face of the bristles as to present the bristles correctly to the surfaces to be brushed, with a natural, unstrained position of the fingers and wrist, irrespective of whether the brush is held in the right hand or in the left hand.

Another object is to provide a toothbrush handle which is so constructed as to permit rotary movement of the handle about its longitudinal axis to be imparted by the thumb and fingers with little or no wrist action.

A particular feature of my brush resides in the symmetrical arrangement around the longitudinal axis of the handle, of more than two relatively broad gripping surfaces disposed at acute angles to the plane of the working surface of the brush.

The accompanying drawing illustrates certain typical embodiments of the invention. Figs. 1 and 2 are side and back views, respectively, of a preferred construction; Fig. 3 is an enlarged transverse cross sectional view on the line 3—3 of Fig. 1; and Fig. 4 is an end view of the same brush, looking up the handle.

Figs. 5 and 6 are back and side views, respectively, of a modified construction.

Fig. 7 is a side view of another embodiment of the invention, showing one manner of holding the brush in use.

Referring first to the construction shown in Figs. 1 to 4 inclusive, my improved toothbrush comprises a head 10 and handle 11 arranged end to end, and having a common longitudinal axis. The head 10 is of substantially flat, elongated form, and carries a plurality of transversely projecting bristle tufts 12. The flat sides of the head, or the central plane which is parallel to one or the other of the sides (i. e., at right angles to the plane of the drawing designated Fig. 1) will be referred to herein, and in the appended claims, as the plane of the head. The ends of the tufts may lie in a generally flat plane, as

shown, or in a curved or irregular plane, and reference to the plane of the working face of the brush is to be understood as denoting a flat plane which contains the ends of the tufts or which comes the closest to containing the ends of all the tufts.

The edges of the head 10 may flare outwardly toward the right as viewed in Fig. 2, to the points 13, where they taper inwardly to form a neck 14.

10 The axis of the handle 11 is substantially straight, and the handle has a gripping portion 15 provided with four gripping surfaces 16 symmetrically arranged around the longitudinal axis of the handle in the form of a diamond or square prism. The surfaces 16 are disposed at acute angles to the plane of the head 10 or to the plane of the working face of the brush. In my preferred construction each of these gripping surfaces is disposed at approximately 45° to the plane of the working face. Depressions 17 of arcuate form, or other gripping means, assist in insuring a comfortable, sure grip on the handle.

20 The gripping surfaces 16 are of substantial area, and are co-extensive in the longitudinal direction so that the brush can be rotated back and forth around the longitudinal axis by the action of the thumb and fingers with little or no wrist action. The centers of the gripping surfaces 16 are equidistant from the head 10, so that, upon the aforesaid rotary movement, the thumb and fingers successively grip different sides of the prism without difficulty and without substantial change in longitudinal position of the grip.

30 35 The end 18 of the handle may be of any suitable configuration, and, as shown, is of square cross section, tapering down from the edge of the grip 15 at first sharply, and then more gradually, terminating in a rounded tip 19.

40 45 The brush shown in Figs. 5 and 6 is similar to that which has been described with reference to Figs. 1 to 4, inclusive, having a gripping portion 20 which is the same as the grip 15 of the first embodiment, except that the depressions 17 are omitted. The end 21 of the handle also is of modified construction, being of flattened form and arranged substantially in the plane of the head 10. The form of the end of the handle is, of course, subject to considerable variation while retaining the principal objects and advantages of my invention.

50 In the form of handle shown in Fig. 7, the gripping portion is of frusto-pyramidal form and tapers into the end 23 in a manner to provide

smooth flat surfaces throughout substantially the entire length of the handle.

The handle and head are made of a suitable plastic or other material, preferably molded in one piece. The bristles are applied to the head in the usual manner. In use, the brush may be grasped in the right hand in the manner shown in Fig. 7, or it may be rotated 90° around its longitudinal axis so as to bring the working face forward into a position to present the bristles naturally to the left side of the teeth, or 90° in the opposite direction so as to present the bristles naturally to the right side of the teeth. By a simple manipulation with the thumb and fingers, and without substantial wrist action, the brush can be turned back and forth between either of these positions and that shown in Fig. 7 so as to brush upwardly over the lower teeth on either side and downwardly over the upper teeth, and to partially rotate the brush for massaging the gums. The same action can be performed with the left hand, so the brush is equally well suited to brushing all of the teeth with either hand. The edges of the prismatic gripping portion assist in the rotary motion about the handle axis, and the flat sides serve, in effect, as stops to bring the working face into proper position for the beginning and end of each stroke. This is true whether the brush is rotated by finger action or by wrist action.

The terms and expressions which I have employed are used as terms of description and not of limitation, and I have no intention, in the use of such terms and expressions, of excluding any equivalents of the features shown and described or portions thereof; but recognize that various modifications are possible within the scope of the invention claimed.

I claim:

1. A toothbrush having a substantially flat, elongated head and a substantially straight han-

5 dle, the head and handle being connected end to end and having a common longitudinal axis, the head having bristle tufts, the ends of the tufts providing a working face, and the handle having a gripping section consisting of four gripping portions symmetrically arranged around said axis in a common transverse section, all of the gripping portions in said common transverse section being arranged in planes which make acute angles with said working face, the width of each gripping portion being substantially equal to the full width of the handle whereby they present broad surfaces serving as stops to bring the working face into proper position for the beginning and end of each rotation stroke about said axis.

10 2. A toothbrush having a substantially flat, elongated head and an elongated handle, the head and handle being connected end to end, the handle having a four-sided gripping portion which is substantially square in cross section with four sharply-defined corners, each of the sides of the square being disposed at an angle of approximately 45° with respect to the plane of the head, and each side of the gripping portion being of substantial width and meeting adjacent gripping portions at an angle of substantially 90° whereby the gripping portions serve as stops to bring the head of the brush into proper position for the beginning and end of each rotative stroke.

15 3. A toothbrush having a substantially flat, elongated head and an elongated handle, the head and handle being connected end to end, the handle having a gripping portion which is substantially square in cross section and presents substantially flat surfaces disposed at acute angles with respect to the plane of the head, the flat surfaces tapering inwardly toward the end of the handle.
